Primary Examiner — George D. Kirschbaum(74) *Attorney, Agent, or Firm* — Norton Rose Fulbright
US LLP(57) **CLAIM**

The ornamental design for a globe for a signal warning and displaying lamp, as shown and described.

DESCRIPTION

FIG. 1 is a front elevational view of a globe for a signal warning and displaying lamp of my new design;

FIG. 2 is a rear elevational view thereof;

FIG. 3 is a right side elevational view thereof and the left side elevational view being a mirror image of the right side elevational view;

FIG. 4 is a top plan view thereof;

FIG. 5 is a bottom plan view thereof;

FIG. 6 is a perspective view taken from the front, top and left side thereof;

FIG. 7 is a perspective view taken from the rear, bottom and right side thereof;

FIG. 8 is cross-sectional view thereof taken along the lines 8-8 in FIG. 1;

FIG. 9 is cross-sectional view thereof taken along the lines 9-9 in FIG. 1; and,

FIG. 10 is a reference illustration of the globe with the translucent portion indicated by inclined lines.

The surface is lined for contour only, and no claim is made to a particular texture. No claim is made to portions not shown in the drawings.

1 Claim, 5 Drawing Sheets(56)
